UNITED STATES PATENT OFFICE.

HENRY C. KIRK, OF BALTIMORE, MARYLAND, ASSIGNOR TO SAMUEL KIRK AND SON, INCORPORATED, OF BALTIMORE, MARYLAND, A CORPORATION.

DESIGN FOR A PAPER CUTTER.

Application filed November 27, 1928. Serial No. 29,041. Term of patent 14 years.

To all whom it may concern:

Be it known that I, HENRY C. KIRK, a citizen of the United States, residing at Baltimore, Maryland, have invented a new, original, and ornamental Design for a Paper Cutter, of which the following is a specification, reference being had to the accompanying drawing, forming part thereof.

In the drawing, Figure 1 shows a plan view of a paper cutter, illustrating the invention; Figure 2, a side view of same; and Figure 3, a section taken on line 3—3 of Figure 1.

I claim:

The ornamental design for a paper cutter as shown.

HENRY C. KIRK.
